Attorney

UNITED STATES PATENT OFFICE

ERNST G. K. ANDERSON, OF EVANSTON, ILLINOIS, ASSIGNOR TO APPLETON ELECTRIC COMPANY, A CORPORATION OF ILLINOIS

STRAP CLAMP TERMINAL

Application filed April 12, 1929. Serial No. 354,516.

The present invention relates to devices for making a good electrically conductive connection between a wire and a pipe or the like as, for example, where a jumper is placed 5 as a shunt across a watermeter; and it has for its object to produce a simple and efficient device of this kind.

The various features of novelty whereby my invention is characterized will herein 10 after be pointed out with particularity in the claims; but, for a full understanding of my invention and of its objects and advantages, reference may be had to the following detailed description taken in connection with 15 the accompanying drawing, wherein:

Figure 1 shows a section of a water pipe system embodying the present invention placed around the meter; Fig. 2 is a side view, on a much larger scale than Fig. 1, 20 showing a fragment of the pipe and one of the terminals; and Figs. 3, 4 and 5 are sections taken on lines 3-3, 4-4 and 5-5 respectively, of Fig. 2.

Referring to Figs. 2, 3 and 4, 1 represents 25 a flat strap having a series of holes 2 distributed lengthwise thereof. One end of the strap is fixed to one of my improved terminal devices. The terminal device comprises a tube flattened at one end, as indicated at 3, 30 so as to be a fit for the end of the strap inserted therein. The inner end of this flattened part, together with the enclosed strap member, is bent laterally as indicated at 4. This bend serves a double purpose: preventing 35 the withdrawal of the strap, and placing the body portion of the terminal device approximately radial to a ring into which the projecting portion of the strap may be bent. The outer end of the terminal member is 40 collapsed so as to leave a tubular socket 5, comparatively small in diameter, extending in the direction of the length of the device, flanked by one or more wings made of two thicknesses of metal lying in contact with 45 each other. In the arrangement shown the tubular part 5 is at the longitudinal center of the device, and it is flanked by two similar wings 6, 6 lying on opposite sides thereof. One end of a wire 7 fits into the tubular socket 50 5. When solder is applied to the joint be-

tween the wire and the socket, it will run along the wire until it reaches the inner end of the strap, thus forming a perfect electrically conductive connection between the strap and the wire.

The flattened part of the terminal device is provided with a hole outwardly beyond the bend. A screw or bolt 8 may be passed through any one of the holes 2 in the strap and through the hole in the terminal device, 55 so as to hold the strap in the form of a loop. Since the combined thicknesses of the two walls of the flattened part of the terminal device and of the interposed strap is considerable, the hole in the terminal device may be 60 screwthreaded so that no nut is required. Since the strap bends easily I prefer to place under the head of the screw or bolt a stiff washer that will distribute the pressure; there being shown such a washer in the form of a 65 channel-shaped piece 9.

It will be seen that when the strap is bent around a pipe or the like and is drawn into intimate contact with the latter by means of the screw or bolt, a good electrically conductive connection will be made between the pipe 70 and the wire.

In Figure 1 I have illustrated my improved device as applied for the purpose of securing 75 a jumper or shunt around a water meter A connected to a supply pipe B and having a discharge pipe C. The wire is long enough to extend from a convenient point on the pipe B to a convenient point on the pipe C. It is fastened to each of these pipes by means of 80 one of my terminals; there being such a terminal fixed on each end of the wire.

While I have illustrated and described with 85 particularity only a single preferred form of my invention, I do not desire to be limited to the exact structural details thus illustrated and described; but intend to cover all forms and arrangements which come within the 90 definitions of my invention constituting the 95 appended claims.

I claim:

1. A terminal device comprising a tubular member flattened at one end to receive a strap and collapsed at the other end into the form 100

of a tube of small diameter flanked by a wing portion.

2. A terminal device comprising a tubular member flattened at one end to receive a strap and collapsed at the other end into the form of a tube of small diameter flanked by a flat wing.

3. A terminal device comprising a tubular member flattened at one end to receive a strap and collapsed at the other end into a central longitudinal tube of small diameter flanked on both sides by wings parallel with the flattened portion at the other end.

4. A strap clamp terminal comprising a strap, a tubular member flattened at one end and fitting over one end of the strap, the inner end of said member and the enclosed strap being bent on a transverse line, a socket at the outer end of said member for receiving a wire, and a detachable fastening device between the free end of said strap and said member outwardly from the bend.

5. A strap clamp terminal comprising a strap, a tubular member flattened at one end and fitting over one end of the strap, said flattened portion and the enclosed part of the strap being bent on a transverse line outwardly from the bend, the outer end of said member being collapsed so as to leave a longitudinal tubular part of small diameter, a wire fitted into said tubular part, and a detachable fastening device between the free end of the strap and the flattened part of said member outwardly from the bend.

35 6. A strap clamp terminal comprising a strap, a tubular member flattened at one end and fitting over one end of the strap, there being a hole through the flattened portion of said member and the strap within the same, the free portion of the strap having a series of holes distributed lengthwise of the same, a bolt adapted to pass through one of the holes in the free portion of the strap and the hole in said member to secure the strap in the 40 form of a loop, the outer end of said member being collapsed into the form of a longitudinal tubular part of small diameter flanked by one or more wings, and a wire fitting into said tubular part.

45 50 In testimony whereof, I sign this specification.

E. G. K. ANDERSON.
